GUY R. POYER, OF WICHITA, KANSAS

TIMING GEARING

Application filed February 21, 1930. Serial No. 430,264.

This invention relates to a timing gearing for internal combustion engines and the primary object is to provide a simple, easily constructed timing gearing particularly designed for internal combustion engines of the radial type. The invention is especially designed but not necessarily limited to radial type aviation engines and the gearing is so constructed that it may easily be applied to 10 the engine block within a circular space already present in this type of engine so that it will not be necessary to supply an extra gear case in order to apply the timing gearing.

15 The invention will be readily understood by reference to the following description in connection with the accompanying drawings in which:

Fig. 1 is a diagrammatical view of the end 20 of a radial engine to which my invention is applied.

Fig. 2 is an enlarged partial elevation of the timing gearing.

Fig. 3 is a cross-sectional view through one 25 of the valve lifter members and through one end of the carrier, the end of the valve lifter being shown in elevation.

Fig. 4 is a partial end view of an opposed crank, staggered cylinder, radial engine to 30 which my invention is applied.

Fig. 5 is a fragmentary enlarged view of a modified form of the invention for the opposed crank, staggered cylinder engine and

Fig. 6 is a modified form of valve lifter.

35 For the purpose of illustration, I have shown the invention in Figure 1 applied to a five-cylinder radial engine, the cylinders being designated by the reference numerals 1, 2, 3, 4 and 5. Each cylinder is provided 40 with an intake valve 6 and an exhaust valve 7. The push rods 8 and 9 are of usual construction as are also the valve lifters 10 and 11 except the modification shown in Figure 6. In other words, the engine proper follows 45 the usual practice.

Located concentrically on the engine block is a fixed internally geared ring 12 and loosely mounted on the crank shaft 13 of the engine is a carrier 14 for the valve lifter 50 actuators. The carrier is shown as having

radial arms 15, 16 and 17 on the ends of which are mounted revolving geared rollers 18, 19 and 20. The rollers can be rotatably supported on the arms by pins or stub shafts 21 but this detail is not important. Each 55 roller has peripheral teeth 22 which mesh with the internal teeth 23 of the ring 12 and which also mesh with the peripheral teeth 24 of a sun gear 25 fast on the crank shaft 13. Each roller has an offset circumferential 60 shoulder or valve lifter engaging portion 26 which rides on the end of the valve lifters to actuate the push rods for the intake and exhaust valves, the latter operating in the usual way. It is to be understood, of course, 65 that the valve lifters are supported in guides following the common practice so it is deemed necessary to illustrate the guides in this application.

Assuming the parts to be assembled and 70 the crank shaft to be rotating in a counter-clockwise direction, the carrier 14 will be rotated in a counter-clockwise direction because the sun gear fixed on the crank shaft is in mesh with the planetating gears 18, 19 75 and 20. The planetating gears, as above indicated, are also in mesh with the internal teeth 23 of the ring gear 12. Therefore, the planetating gears or rollers will revolve about the axis of the crank shaft in a counter- 80 clockwise direction but they will rotate on their own axes in a clockwise direction. The inner ends of the valve lifters will overlap the inner edge of the ring gear 12 so that as the planetating gears revolve about the 85 axis of the crank shaft, the shoulders or roller portions of certain of the planetating gears will alternately engage the valve lifters for the exhaust and intake valves of some of the cylinders while another roller is alternately opening the intake or one cylinder 90 and moving over to open the exhaust of another cylinder as indicated in Figure 1. Therefore, some of the cylinders are exhausting, some cylinders have both valves closed 95 and some cylinders are taking in fuel at the same time following the known practice of this type of motor. The gears will have the proper ratio to effect the proper timing as will be well understood.

It will be observed that with the construction shown, a camming action is obtained for the valve lifters by a circumferential actuator such as a roller. The rollers ride into contact with the valve lifters and since the roller surfaces are generated on symmetrical curves, there will be no friction between the actuator and the valve lifter as would be present where an irregular surface such as a cam surface is employed nor will there be liability of shocks to induce pounding of the valves on their seats.

In Figures 4 and 5, I have shown the invention arranged for a twin-cylinder engine, that is, where a double bank of cylinders is employed using crank shafts with opposed cranks one hundred and eighty degrees apart. In this construction, the valve lifters will have heads, each operating two push-rods. The valve lifter 10^a in Figure 5 is shown as provided with a head 27 having seats 28 to operate two push-rods 29 and 30. The push-rod 29 will open the exhaust of one cylinder of one bank while the rod 30 is opening the inlet valve of one cylinder of the other bank. In all other respects, the modification operates in accordance with the preferred form.

Under certain conditions, I may find it advisable to have a relatively slow lift of the valve lifters, a relatively short period when the valve will be standing wide open and a relatively slow closing of the valve. The word "relatively" is used advisedly having in mind that in any internal combustion engine, the opening and closing movements of any valves are comparatively rapid.

In Figure 6 I have shown a modified form of valve lifter designated 31 with a cross-head 32 provided with a central flat lower portion 33 and two curved end portions 34 and 35. As the rollers ride on 34, the angle of the curve is such that the valve lifter will begin to move outwardly relatively slow because the curve 34 approaches the curve of the contour of the roller. As the valve lifter starts to move, the roller will roll on the straight middle portion to effect the maximum lift on the valve lifter, then, it will ride off on the curved portion 35 and finally leave the valve lifter without having induced any shock or pounding thereto. Obviously, the end of the valve lifter 31 may partake of different shapes to meet the desired conditions under which the motor is to operate.

It might be well to state here that the ratio between the sun gear and the planetating gears for a five-cylinder engine will be approximately six to one and that for a different number of cylinders, a different gear tooth ratio will be used, the ratio in each case being one in excess of the number of cylinders employed for one bank.

From the foregoing it will be apparent that the timing gearing is simple in construc-

tion, that it is easily assembled and that it may be readily applied to existing types of radial engines without the necessity of materially altering the engine and that the shocks to valve lifters, push rods and valves will be reduced to a minimum if not entirely eliminated.

What I claim and desire to secure by Letters-Patent is:—

1. A timing gearing for internal combustion engines comprising a carrier rotatable about a common axis and revolving valve lifter actuators mounted on the carrier in spaced relation, said lifters comprising planetary gears having valve lifter engaging portions.

2. A timing gearing for internal combustion engines comprising a carrier rotatable about a common axis and revolving valve lifter actuators mounted on the carrier in spaced relation, said lifters comprising planetary gears having concentric valve lifter engaging portions.

3. A timing gearing comprising an internally toothed ring gear, a sun gear concentric with the ring gear, planetating gears meshing with the sun gear and the ring gear and valve lifter engaging portions on the planetating gears.

4. A timing gearing comprising an internally toothed ring gear, a sun gear concentric with the ring gear, planetating gears meshing with the sun gear and the ring gear and concentric valve lifter engaging portions on the planetating gears.

5. A timing gearing comprising an internally toothed ring gear, a sun gear concentric with the ring gear, planetating gears meshing with the sun gear and the ring gear and circular valve lifter engaging portions rigid with but offset from the planetating gears.

6. A timing gearing for internal combustion engines comprising a carrier having radial arms and revolving valve lifter actuators carried by the ends of the radial arms.

7. A timing gearing comprising a rotatable member having radial arms, revolving valve lifter engaging rollers carried by the arms and means for positively driving said rollers.

8. A timing gearing for internal combustion engines comprising a carrier rotatable about a common axis, revolving valve lifter actuators mounted on the carrier, valve lifters having portions to be engaged by the actuators and means on the valve lifters for actuating a plurality of push rods.

9. A timing gearing comprising a rotatable member, revolving valve lifter actuators mounted on the member and independently rotatable and valve lifters having curved portions on their lower ends offset with respect to the longitudinal centers of the valve lifters.

10. A timing gearing for internal combustion engines comprising a rotatable carrier, valve lifter actuators mounted on the carrier having independent rotative movement and
5 valve lifters radially disposed about the carrier having cam-shaped ends.

In testimony whereof I affix my signature.
GUY R. POYER.
